COSMETIC APPLICATOR

Louise R. Catelin, New York, N. Y.

Application June 16, 1939, Serial No. 279,476

2 Claims. (Cl. 132—1)

My invention relates to improvements in cosmetic applicators, and more particularly to means for applying lipstick material to the lips.

For the purpose of illustrating my invention, an embodiment thereof is shown in the drawing, in which:

Figure 1 is an elevational view, partly broken away, of a cosmetic applicator constructed in accordance with my invention;

Fig. 2 is a fragmentary, elevational view, illustrative of the manner of using my improved cosmetic applicator; and

Fig. 3 is an elevational view, partly in section, showing the manner in which my improved cosmetic applicator may be associated with a lipstick crayon.

With reference to Fig. 1, my improved cosmetic applicator comprises an elongated plate 10 made of metal or any other suitable, relatively rigid material. The longitudinal edge 12 of the plate 10 is shaped as shown, to conform to the contour of the upper lip 14. The other and opposite longitudinal edge 16 of the plate 10 may be shaped as shown, to conform to the contour of the lower lip 18.

The front surface 20 of the plate 10 is shaped to conform to the upper lip 14 when the plate 10 is pressed against the same, as shown in Fig. 2.

The cap or casing 22 for a lipstick crayon 24 may serve as the means for supporting and manipulating the plate 10. In such case, I propose to pivotally connect the plate 10 to the upper end of a standard 26 fixed with respect to the casing 22. The pivotal connection is made by a pin 28 with which the plate 10 is provided at the back surface thereof. The head of the pin is riveted over as shown in Fig. 2, to make a fairly tight, pivotal connection so that the plate 10 will hold its angular position with respect to the standard 26.

When not in use, the plate 10 is turned to the position shown in Fig. 3 so that a protective cover 30 may be placed over the plate and pushed onto the adjacent end of the casing 22 with a snug fit.

In using my improved cosmetic applicator, the cover 30 is removed and the plate 10 turned to the position shown in Fig. 1. The crayon 24 is withdrawn from its casing 22, and a uniform coating of the lipstick material is applied to the front surface 20 of the plate 10. The casing 22 serving as a handle, the plate 10 is now pressed against the upper lip 14, as illustrated in Fig. 2,

with the plate in position so that the longitudinal edge 12 is in position to form a perfect lip contour. The lipstick material is thus transferred to the lip. Transfer of the lipstick material might be facilitated by giving the casing or handle 22 a slight downward movement. 5

I claim as my invention:

1. A cosmetic applicator comprising a relatively rigid and elongated plate having a longitudinal edge thereof shaped to conform to the contour of the upper lip, means for supporting said plate and providing a handle for manipulating the same, said supporting means being provided at one end thereof with a standard, means for connecting said plate to the free end of said standard and adapted to permit placement of said plate in position substantially in alignment with the respective longitudinal axes of said standard and said supporting means, and a protective covering member having one end thereof open for placement over said plate and said standard to protect the same and for fitting relation with respect to the adjacent end of said supporting means whereby said covering member and said supporting means are held in combined relation with respect to each other. 25

2. A cosmetic applicator comprising a relatively rigid and elongated plate having a longitudinal edge thereof shaped to conform to the contour of the upper lip, means for supporting said plate and providing a handle for manipulating the same, said supporting means being provided at one end thereof with a standard, means pivotally connecting said plate to the free end of said standard for permitting either pivotal movement of said plate into position substantially in alignment with the respective longitudinal axes of said standard and said supporting means or pivotal movement of said plate into position substantially perpendicular with respect to said axes, said pivotal connecting means being relatively tight to hold said plate in said second-named position thereof, and a protective covering member having one end thereof open for placement over said plate and said standard when said plate is in said first-named position thereof to protect said plate and said standard and for fitting relation with respect to the adjacent end of said supporting means whereby said covering member and said supporting means are held in 50 combined relation with respect to each other. 45

LOUISE R. CATELIN.
